UNITED STATES PATENT OFFICE.

CHARLES C. JACOBS, OF CHICAGO, ILLINOIS, ASSIGNOR TO F. C. AUSTIN DRAINAGE EXCAVATOR COMPANY, OF CHICAGO, ILLINOIS, A CORPORATION OF ILLINOIS.

DREDGE.

No. 890,909.

Specification of Letters Patent.

Patented June 16, 1908.

Application filed June 26, 1907. Serial No. 380,973.

To all whom it may concern:

Be it known that I, CHARLES C. JACOBS, a citizen of the United States, residing at Chicago, in the county of Cook and State of Illinois, have invented certain new and useful Improvements in Dredges, of which the following is a specification.

My invention relates to improvements in dredges and aims to provide means for rapidly excavating or dredging the material to be removed and for cutting the banks or embankments so that they will be smooth and have the desired inclination.

Other objects of my invention will be come apparent from the accompanying drawings, forming a part of this specification, taken in connection with the description given below.

On the forward end of a scow or boat I mount a rotatable turntable, also providing on the boat suitable motive power for turning the table and for actuating and adjusting the excavating mechanism. Hinged to this turntable is a vertically-adjustable trackway shaped, in part at least, to conform to the bottom of the excavated water course and inclined in part to correspond to the desired inclination or slope of the bank. This trackway and the sharp-edged excavating bucket or shovel adapted to reciprocate thereon, together with the dumping mechanism, are substantially like or similar to the corresponding parts of the excavating machine set forth in my former patent No. 829,214, granted August 21, 1906. As the bucket is caused to travel forwardly on the shaped trackway or templet it removes earth from the bottom of the river-bed or harbor, and when the trackway is in certain cross or lateral positions it also scrapes off layers of earth from the adjacent bank of the water course. After the bucket has received its load of dirt, the trackway and turntable are rotated so as to bring the forward upper end portion of the trackway over the bank, whereupon the dumping operation occurs and the excavated dirt is discharged upon the bank.

On the drawings Figure 1 is a side elevation of my improved dredge, the boat or scow being shown in longitudinal section; Fig. 2 is a plan view of the dredge; Fig. 3 is a plan view of the boat and turntable on an enlarged scale; Fig. 4 is a longitudinal section of the boat on the same scale; Fig. 5 is a plan

view of the excavating portion of the dredge; Fig. 6 is a side elevation of the same; and Fig. 7 is a front end elevation of the dredge showing the shaped trackway swung to one side, its outer end reaching over the adjacent bank.

My improved dredge includes a scow or flat-bottom boat 10 having at its fore end a platform 11 braced and held in position by one or more bracket or brace bars 12. Rotatable on this platform is a turntable 13 having on its under face a plurality of wheels or rollers 14 adapted to travel on a circular trackway on the platform. A pair of shaped plates or tracks 15 suitably spaced apart and held together by a framework 16 are hinged at 17 to the turntable so as to rotate therewith. This guiding trackway, its dumping portion 18, the sharp-edged excavating bucket 19, and its truck 20 adapted to reciprocate on the trackway, are substantially like the corresponding parts set forth in detail in my former patent No. 829,214, rendering a further description thereof unnecessary here. The trackway 15 is adjustable vertically, turning about its hinges 17, by means of a cable 21 passing around pulleys 22 and 23, the former being connected by a cable or cord 25 to a substantially upright support formed of two inclined bars 24 suitably mounted and braced or stayed on the boat and united at the top ends, while the other pulley 23 is connected to the forward or outer end of the trackway by a similar cable 26. Cable 21 passes beneath a guide pulley 27 at or near the middle of the turntable and then continues between two adjacent horizontal guide pulleys 28 to a drum 29 on the boat, upon which it may be wound up and from which it may be paid out, as desired, thereby accomplishing the vertical adjustment of the trackway. The truck 20 of the sharp-edged open-mouthed excavating bucket or shovel 19 has attached to its front end a forwardly-pulling or advancing cable 30 which passes around a guiding pulley 31 at the outer end of the trackway and over a similar pulley 32 at the top end of the support 24, also passing between two laterally guiding pulleys 33 at the same place. Cable 30 continues on down to a drum 34 on the boat. A retracting cable 35 for the bucket and truck is attached to the rear end of the latter and passes over a guiding sheave 36 and between a pair of horizontal sheaves 37 110

to a similar drum 38, upon which it may be wound and from which it may be unwound.

In order to rotate the turntable and the attached guiding trackway, I pass a cable 39 around the circular turntable and wind the remaining portion of the same upon a drum 40 in such manner that the rotation of the drum in one direction causes the winding up of one part of the cable and a paying out of the other, while a rotation of the drum in the opposite direction causes a paying out of that part of the cable which was formerly wound up and a winding up of the other part of the cable, whereby by rotating or turning the drum 40 in one direction or the other, the turntable and its attached excavating trackway and shovel may be swung laterally in either direction. In its passage to drum 40 cable 39 is guided by the pair of pulleys 41.

To hold the scow or boat in position during the excavating operation I provide the same with a plurality of pointed vertically slideable spuds or posts 42, 43, and 44, the latter being at the rear end of the boat. In order that these spuds or anchoring posts may be easily raised out of the ground, so that the position of the boat may be changed, I fasten to them cables or cords 45, 46, and 47, respectively; adapted to be wound upon and unwound from drums 48, 49, and 50, respectively, suitable guiding sheaves or pulleys being provided for directing the cables to their drums. Ordinarily these spuds or holding posts will sink into the ground sufficiently to hold the boat in position, but it requires some power to lift them out of the ground or mud, and consequently I have provided the cables and drums specified, the latter being mounted on a shaft 49. To operate the various drums and cables, the boat is supplied with a steam boiler 50^a supplying steam to an engine 51 connected to a longitudinal rotary shaft 52. Shafts of the various drums are provided with means for connecting them either temporarily or permanently with the shaft 52, clutches being provided where necessary. The details of this part of the mechanism are well understood in the art and need no further description.

The operation of my improved dredge and excavator is substantially as follows: The boat or scow having been brought to the desired position, the spuds are lowered to anchor the boat in place. Assuming that the truck and excavating shovel are near the rear end of the guiding track 15, the engine is started in the proper direction to cause a winding up of cable 30 on drum 34 and a paying out of cable 35 from the adjacent drum 38. By this means the shovel and truck are caused to travel forwardly on the guiding trackway, and during this movement the shovel scrapes or shaves off a layer of dirt from the bottom, and during a portion of the travel up the outer incline of the trackway. After the

shovel has received its load, the turntable, trackway, and shovel are swung laterally so as to bring the outer end of the trackway over the adjacent bank, as shown in Fig. 7. This rotation of the turntable and trackway is accomplished by throwing a clutch into operation so as to cause rotation of drum 40 in the proper direction. Further travel of the truck and shovel on the inclined end portion of the trackway causes it to discharge its load, as shown in Fig. 7 and as fully set forth in my former patent No. 829,214. If desired, the swinging of the turntable and the travel of the shovel and its truck on the upper inclined portion of the trackway may occur simultaneously. The turntable and trackway are then swung back to their original position, and as the excavating or dredging proceeds, the trackway and its frame are fed downwardly step by step by the paying out of cable 21 from drum 29 so that the shovel is permitted to shave off successive layers of dirt. When the excavating or dredging is done with the trackway swung to one side, as shown in Fig. 7, or it may be done with the trackway in some other position depending upon the position of the boat, the slope of the adjacent bank is made equal to the incline of the end portion of the trackway, this latter being in the first place made with the inclination which it is intended the bank of the water-course or river should have. The middle portion of the guiding track, as will be observed, is substantially horizontal when the trackway is in its lowermost position so as to give the bottom of the water-course a substantially flat and horizontal surface.

As is well understood by those skilled in this art, the mechanical features of my improved dredge may be varied and modified to a considerable extent without sacrificing the benefits and advantages or departing from the substance of my invention.

I desire to direct attention to the fact that, instead of placing the turntable and shovel guiding and supporting trackway on a boat or scow, it may be placed on an ordinary car or on any other form of vehicle.

I claim:

1. In a dredge, the combination of a boat, a trackway hinged to said boat and shaped in part at least to conform to the desired inclination of the bank, an excavating bucket adapted to travel on said trackway, and means to actuate said bucket, substantially as described.

2. In a dredge, the combination of a boat, a vertically-adjustable trackway hinged to said boat and shaped in part at least to conform to the desired inclination of the bank, an excavating bucket adapted to travel on said trackway, and means to actuate said bucket, substantially as described.

3. In a dredge, the combination of a boat,

a trackway having a horizontal portion and a part shaped to conform to the desired inclination of the bank hinged to said boat, an excavating bucket adapted to travel on said trackway, and means to actuate said bucket, substantially as described.

4. In a dredge, the combination of a boat, a trackway mounted on said boat so as to swing laterally and shaped in part at least to conform to the desired inclination of the bank, an excavating bucket adapted to travel on said trackway, and means to actuate said bucket, substantially as described.

5. In a dredge, the combination of a boat, a turntable on said boat, a guiding trackway mounted on said turntable; means to rotate said turntable, an excavating shovel adapted to travel on said trackway, and means to actuate said shovel, substantially as described.

6. In a dredge, the combination of a boat, a turntable mounted on said boat, means to

rotate said turntable, a vertically-adjustable shovel-supporting and guiding trackway hinged to said turntable, a shovel adapted to travel on said trackway, and means to actuate said shovel, substantially as described.

7. The combination of a support, a shovel-supporting and guiding trackway mounted on said support so as to swing laterally, an excavating shovel adapted to travel on said trackway, and means to actuate said shovel, substantially as described.

8. The combination of a support, a turntable mounted on said support, a shovel-supporting and guiding trackway mounted on said turntable, an excavating shovel adapted to travel on said trackway, and means to actuate said shovel, substantially as described.

CHARLES C. JACOBS.
